UNITED STATES PATENT OFFICE.

CHARLES B. CLARK, OF DETROIT, MICHIGAN.

SASH-HOLDER.

SPECIFICATION forming part of Letters Patent No. 247,310, dated September 20, 1881.

Application filed July 26, 1881. (Model.)

To all whom it may concern:

Be it known that I, CHARLES B. CLARK, a citizen of the United States, residing at Detroit, in the county of Wayne and State of Michigan, have invented new and useful Improvements in Sash-Locks, of which the following is a specification.

My invention relates to that class of sash-locks in which the sash is held at any desired elevation by means of a pair of spring-jaws, which are provided with a pair of levers fulcrumed by means of a pin passing through the levers and the lock-case.

The object of my improvement is to dispense with the fulcrum-pin heretofore employed, and to provide enlarged bearings in the walls of the lock-case, and also to furnish a cheap, strong, and effective sash-lock and lock-case.

To such end it consists, first, in a pair of levers adapted to constitute expandible jaws and handles, and formed with disks received into cup-shaped recesses formed in the lock-case to serve as bearings for the disks; second, in a pair of levers in the sash-lock, each formed with a concavity about intermediate of its ends, and a disk formed alongside of each concavity, whereby, when said levers are brought together and inclosed within the lock-case a chamber for the spring will be formed between the opposing faces of the two disks and the walls of the said concavities; third, in the combination, with a pair of levers provided with expandible jaws with curved or segment-shaped ends, in a sash-lock, of a stop-plate adapted to be secured to the window-frame and formed with concavities to receive the ends of the jaws and with a stud or projection intermediate of the said concavities, substantially as hereinafter described.

In the drawings, Figure 1 is a side view of a sash-lock constructed in accordance with my improvement and applied to a window-sash. Fig. 2 represents the lock with the cap-plate removed. Fig. 3 is a transverse section taken through the lock on the line $x x$, Fig. 1. Fig. 4 represents, in perspective, the under side of the cap-plate. Fig. 5 is a like view of the base-plate, and Fig. 6 is a perspective view of one of the levers.

The pair of levers A A employed in this sash-lock are fulcrumed at points about intermediate of their ends, so as to provide a pair of expandible jaws, $a a$, projecting from one side of the lock-casing, and a pair of handles, $a' a'$, projecting from the opposite side of the casing, 55 for operating the said expandible jaws. These jaws are closed or retracted to within a short distance of each other by means of a spring arranged to act against the same within the lock-casing, and the jaws are expanded or moved 60 apart by the application of pressure upon their handles.

The outer ends of the jaws are each formed with a curved or segmental bearing-face, a^2 , and to the window-frame or confining-strip are 65 secured any desired number of stop-plates, B, each of which is formed with two concaved portions, $b b$, to receive the curved ends or faces a^2 of the jaws. The stop or check plate is also formed with a lug or projection, b' , intermediate of its two concavities, the said lug or projection being gripped between the ends of the jaws when the lock is brought opposite to such stop or check plate.

In some instances the expandible jaws of a 75 sash-lock belonging to this class have been provided with enlarged ends, which bear directly upon the window-frame or confining-strip and are jammed against the same by the action of a spring. While in the present sash-lock to 80 which my improvement is applied the jaws might be so employed, yet I prefer the stop-plate herein shown, since a positive adjustment in the height of the window-sash is thereby always secured.

In my sash-lock the levers A are not fulcrumed by means of the usual fulcrum-pins, but have their fulcral bearings formed by the walls of the cup-shaped recesses sunk in the two plates which constitute the lock-casing, 90 the levers being cast with annular disks having their peripheral bearing-surfaces adapted to bear against the walls of the said recesses, thereby affording broad bearings, and also obviating the strain upon a single fulcral pin, as 95 heretofore. Each lever is formed with a concavity, C, alongside of which is the disk D, constituting a wall at one side of such concavity. A portion of each disk projects from the lever with which it is cast, so that when the 100 two levers are confined or coupled together within the lock-casing the disk of one lever

will rest against one side of the other lever, while the disk of the said latter-mentioned lever will rest upon that side of the former lever which is opposite to the side thereof from which its disk projects. Under this construction an annular chamber, E, for confining a coiled spring, F, will be formed between the two levers when they are brought together in proper position, the ends of said spring extending a short distance out from said chamber, so as to bear against the handle ends of the lever, in order to force the handles apart and thereby close their jaws.

It will be seen that the union of the disks D and their respective levers occurs at the sides of the disks, whereby the latter have each a continuous peripheral bearing-surface, d, which fits within the cup-shaped recesses g g' of the plates G G', constituting the two portions of the lock-case. The outer or cap plate, G, of the lock-case is formed with lugs or ears g' g', made with holes, through which screws are passed to secure the case to the sash, while the inner or foundation plate of the case has its ends adapted to seat into notches g², formed in the inner sides of said lugs of the outer plate. This construction would of itself hold the two plates together after the application of the case to a window-sash; but in order to secure the plates together prior to such application, I pass a rivet, H, through the two plates and through holes formed through the disks of the levers. This rivet does not, however, constitute a fulcrum-pin for the levers, but serves merely to hold the two parts of the lock-case together.

It will be observed that this construction of

lock-case is exceedingly simple and cheap, and that the drilling incident to the production of ordinary lock-cases is avoided. The disks bearing in the cup-shaped recesses incur such strain as has heretofore been borne by a pin, and hence not only is the mechanism rendered stronger, but also it works much easier under all circumstances.

What I claim is—

1. In a sash-lock, a pair of levers adapted to constitute expandible jaws and handles, and formed with disks received into cup-shaped recesses formed in the lock-case to serve as bearings for the disks, substantially as described.

2. In a sash-lock, the pair of levers A, each formed with a concavity, C, and a disk alongside of such concavity, whereby, when said levers are brought together and inclosed within the lock-case, substantially as described, a chamber, E, for the spring, will be formed between the opposing faces of the two disks and the walls of the said concavities, substantially as described.

3. In a sash-lock, the combination, with a pair of levers provided with expandible jaws with curved segment-shaped ends, of a stop-plate formed with concavities to receive the ends of the said jaws, and also formed with a stud or projection intermediate of said concavities, substantially as described.

In testimony whereof I have hereunto set my hand in the presence of two subscribing witnesses.

CHARLES B. CLARK.
